UNITED STATES PATENT OFFICE.

JOHN PRICE WETHERILL, OF SOUTH BETHLEHEM, PENNSYLVANIA.

MAGNETIC SEPARATOR.

SPECIFICATION forming part of Letters Patent No. 708,186, dated September 2, 1902.

Application filed August 26, 1901. Serial No. 73,298. (No model.)

To all whom it may concern:

Be it known that I, JOHN PRICE WETHERILL, a citizen of the United States, residing at South Bethlehem, county of Northampton,

5 State of Pennsylvania, have invented certain new and useful Improvements in Magnetic Separators; and I do hereby declare the following to be a full, clear, and exact description of the invention, such as will enable others skilled in the art to which it appertains to make and use the same.

In an application for Letters Patent of the United States filed of even date herewith, Serial No. 73,297, I have described and claimed, 15 broadly, an apparatus for effecting the magnetic separation of fines and other ore mixtures containing magnetic and relatively non-magnetic or diamagnetic material by the expedient of feeding the material to be separated into the interpolar space or gap formed between two magnet-poles, washing out by the aid of water-jets the non-attracted material and removing and separately collecting the material magnetically detained in the interpolar space by means of scraper-blades.

25 My present invention consists in another form of apparatus operating upon the same general principle, but of different specific construction. In still another application, also filed of even date herewith, Serial No. 73,299, I have described and claimed another form 30 of apparatus, likewise embodying the same general principle, but of different specific construction.

35 In the accompanying drawings, Figure 1 represents a vertical section of an apparatus embodying the invention, the magnet-coil and the parts immediately adjacent thereto being shown in elevation. Fig. 2 represents 40 a top plan view with the main body portion of the upper magnet-pole removed. Figs. 3 and 4 represent details.

Similar letters of reference indicate similar parts throughout the several views.

45 Referring to the drawings, A indicates a vat or tank adapted to contain a body of water designed normally to rise to about the level indicated in Fig. 1. Within the vat or tank A extend the polar projections of an 50 electromagnet, the coil B of the electromagnet being exterior thereto, so as to be out of contact with the water. For convenience of

construction the core C of the electromagnet is made separate from the pole-pieces, but is united thereto by means of the connecting-bolts a. The polar projections may conveniently be made of hollow tubing, as shown, flattened along the horizontal portions D D' and preserving its original diameter at the vertical portion E E', the arrangement being 60 such that the interpolar space or gap is submerged a suitable distance below the water-level in the tank.

Both the upper and the lower tubular pole-pieces E E' are cut away at diametrically opposite points, and the magnetic metal thus removed is replaced by like sections b b', of brass or other non-magnetic material, of the general form of a triangular prism, the broader bases of the prisms facing each other, as 70 shown. The general effect of this expedient is to practically interrupt the flow of magnetism across the space occupied by the sections b b' and to concentrate the lines of force across the gap separating the intervening sections of magnetic material. This concentration of the lines of force is further increased by giving to the ends of the pole-pieces a pointed or wedge-shaped configuration, so that 75 a magnetic field of a high degree of concentration is formed between each pair of the opposing magnetic sections. Into the magnetic fields of force thus formed I feed the material to be separated. This may conveniently be done by means of hoppers G, exterior to the interpolar spaces, said hoppers being provided with the usual feed-rollers c, operated in any suitable manner—as, for instance, by the bevel-gears H—and the material may be distributed with a considerable 80 degree of uniformity to the interpolar spaces by means of corrugated or fluted feed chutes or aprons f.

Within the interior of the polar extensions E E' is located an upright shaft, whose lower portion F is stepped within a suitable bearing g and whose upper portion J is hollow and bears the driving-pulley K. The hollow portion J is adapted to receive water from any suitable source of supply and to distribute the same through the hollow radial arms h to a bustle-pipe L, which pipe is provided with a series of jet-apertures adapted to discharge the water in the form of jets radially

outward through the interpolar space or gap. The pipe L, preferably of brass, is furthermore provided with a series of brass scraper-blades *m* of a general configuration conforming to the shape of pointed or wedge-shaped ends of the polar projections, as shown.

Exterior to and opposite each of the non-magnetic sections of the polar projections are the receiving-hoppers M, into which the scraping-blades convey the major portion of the magnetic particles separated. Such other portions of the magnetic particles as creep within the hollow magnet are received in an inner hopper N, and the main body portion 15 of the tailings or non-attracted particles are received in the lower hopper P. All of these hoppers are provided with discharge-gates at their lower ends, as shown.

The operation of the apparatus is as follows: Magnetic fields of suitable concentration being established across the interpolar spaces or gaps, the material to be separated is fed at a predetermined rate from the hoppers G, by means of the feed-rollers *c* and fluted aprons *f*, into said interpolar spaces. At the same time water is admitted into the hollow portion J of the shaft and is directed in the form of a series of jets outwardly through the interpolar spaces, and at the same time the shaft is set in rotation. The magnetic particles of the material to be separated are attracted by the magnet-poles and are detained thereat, whereas the non-attracted portions mechanically entangled with them are washed out by the impact, and dissolving action of the water-jets directed through the mass and falling through the water in the vat are received in the hopper P. As the shaft revolves the scraper-blades *m* convey the attracted and detained magnetic particles or heads toward the non-magnetic sections *b b'* of the polar projections, and as the magnetic particles enter the space between opposite sections *b b'* they leave the magnetic field of force and being no longer detained by magnetic attraction fall into the hoppers M N, arranged for their reception. It will of course be understood that the operation is a continuous one, progressing uniformly as long as material is fed from the hoppers G while the central shaft is rotated.

My invention is particularly applicable to the treatment of "fines," which are difficult of separation by ordinary forms of apparatus. It is not, however, restricted to this use, but may be employed for the separation of material of any suitable size or mesh.

Having thus described my invention, what I claim is--

60 1. A magnetic separator, comprising oppositely-disposed hollow magnet-poles, separated by an interpolar space or gap traversed by the magnetic lines of force, means for feeding into said gap the material to be separated, means 65 for washing out the non-attracted particles from the particles detained by magnetic attraction in said gap, and a scraper for remov-

ing the attracted particles beyond the detaining influence of the magnetic field; substantially as described.

70 2. A magnetic separator, comprising oppositely-disposed hollow magnet-poles, separated from each other by an interpolar space or gap traversed by the magnetic lines of force said poles having alternate magnetic and non-magnetic zones or sections along their peripheries, means for feeding into the interpolar space or gap the material to be separated, means for washing out the non-attracted particles from the particles detained by magnetic attraction in the gap, and a scraper operating in the gap for removing the attracted particles from the magnetic to the non-magnetic sections of the pole-pieces and releasing them thereat; substantially as described.

75 3. A magnetic separator, comprising oppositely-disposed hollow magnet-poles, separated by an interpolar space or gap traversed by the magnetic lines of force, said poles having alternate magnetic and non-magnetic zones or sections along their peripheries, feeding-hoppers for supplying the material to be separated to the magnetic portions of the gap between the magnetic zones or sections, a water-jet pipe having its jet-apertures directed 80 through the gap, and a series of scraper-blades operating within the gap; substantially as described.

85 4. A magnetic separator, comprising oppositely-disposed hollow magnet-poles, separated by an interpolar space or gap traversed by the magnetic lines of force, said poles having alternate magnetic and non-magnetic zones or sections along their peripheries, the non-magnetic zones or sections being of approximately 90 the form of triangular prisms so as to concentrate the lines of force through the magnetic zones or sections, means for feeding the material to be separated to the magnetic portions of the gap, means for washing out the non-attracted particles from the particles detained by magnetic attraction in the gap, and a scraper operating in the gap for removing the attracted particles from the magnetic to the non-magnetic sections of the pole-pieces and 95 releasing them thereat, substantially as described.

100 5. A magnetic separator, comprising oppositely-disposed hollow magnet-poles, separated by an interpolar space or gap traversed by the magnetic lines of force, said poles having alternate magnetic and non-magnetic zones or sections, hoppers for feeding the material to be separated into the magnetic portions of the gap, a rotatory hollow shaft with- 105 in the magnet-poles, an annular jet-pipe carried by said shaft and in communication with its hollow interior, and scraper-blades operating in the interpolar gap and mounted upon said annular pipe; substantially as de- 110 scribed.

115 6. A magnetic separator, comprising oppositely-disposed hollow magnet-poles, separated by an interpolar space or gap traversed

by the magnetic lines of force, said poles having alternate magnetic and non-magnetic zones or sections, hoppers for feeding the material to be separated into the magnetic portions of the gap, a rotatory hollow shaft within the magnet-poles, an annular jet-pipe, carried by said shaft and in communication with its hollow interior, scraper-blades operating in the interpolar gap and mounted upon said annular pipe, receiving-hoppers for heads arranged opposite the non-magnetic sections of the pole-pieces, and a separate receiving-hopper for tailings; substantially as described. 7. A magnetic separator, comprising oppositely-disposed hollow magnet-poles, separated by an interpolar space or gap traversed by the magnetic lines of force, said poles having alternate magnetic and non-magnetic zones or sections, hoppers for feeding the material to be separated into the magnetic portions of the gap, a rotatory hollow shaft within the magnet-poles an annular jet-pipe carried by said shaft and in communication with

its hollow interior, scraper-blades operating in the interpolar gap and mounted upon said annular pipe, receiving-hoppers for heads arranged opposite and outside of the non-magnetic sections, an additional receiving-hopper for heads arranged within the lower magnet-pole, and a separate receiving-hopper for tailings; substantially as described. 25

8. A magnetic separator, provided with an electromagnet having a flattened core and flattened lateral projections from said core, said flattened projections terminating in hollow tubular pole-pieces, separated from each other by an interpolar space or gap traversed by the magnetic lines of force; substantially as described. 35

In testimony whereof I affix my signature 40 in presence of two witnesses.
